UNITED STATES PATENT OFFICE.

JACOB DOELCHER, OF HILLSDALE, MICHIGAN.

PORTABLE ELEVATOR.

Application filed April 23, 1924. Serial No. 708,366.

The present improvements, relating, as indicated, to portable elevators, have more particular regard to an elevator of this type adapted for use in loading freight cars and 5 more especially box freight cars. The object of the invention is to provide an apparatus or mechanism of this type which will be simple and compact in construction, that may be easily moved about and in which 10 the raising and lowering of the platform may be conveniently controlled, the height to which the platform is thus raised being variable to suit the occasion.

To the accomplishment of the foregoing 15 and related ends, the invention, then, consists of the means hereinafter fully described and particularly pointed out in the claims, the annexed drawings and the following description setting forth in detail certain 20 mechanism embodying the invention, such disclosed means constituting, however, but one of various mechanical forms in which the principle of the invention may be used.

In said annexed drawings:—
25 Fig. 1 is a side elevation of a portable elevator embodying my present improvements; Fig. 2 is a plan view of the operating mechanism of such elevator; Fig. 3 is a transverse section of a portion of such mechanism 30 taken on a somewhat larger scale, the plane of the section being indicated by the line 3—3, Fig. 1; and Fig. 4 shows a slightly modified construction.

The particular elevator illustrated in the 35 foregoing drawings has been designed for loading cakes of ice into box freight cars, in which use it is of course desirable that as one tier of such cakes is delivered, e. g. onto the floor of the car, the cakes for the 40 next tier should be raised to a higher level so as to be conveniently delivered on top of the previous tier. It will be understood, however, that the illustrated construction is not limited to elevating cakes of ice but 45 is equally adaptable for use in handling other similar articles.

The frame of the elevator, as illustrated, comprises a base 1 of general rectangular form from which rise two channel bars 2 50 spaced a suitable distance apart, the channel faces of such bars being directed inwardly, as shown in Fig. 2. These bars will be suitably braced at their lower ends on the truck 1 as by angle bars 3 and are 55 connected at their upper ends by a cross bar 4. A platform 5 is vertically slidably held

between the channels 2 by means of guide blocks 6 attached to the respective sides of such platform, as will be readily understood. For the purpose of raising and lowering 60 the platform, two cables 7 are employed, these being attached to eye bolts 8 in such guide blocks 6, respectively, thence passing over sheaves 9, suitably supported at the upper ends of the channels 2, and finally 65 being respectively attached to winding spools 10. The latter are mounted on a cam-shaft 11 that is disposed transversely of and suitably journaled upon a horizontally 70 projecting frame 12 that is carried by the channel members 2 at a convenient elevation above the truck 1, or in other words above the surface on which the elevator as a whole is supported. The frame 12, it will be noted, projects far enough from the channels 2 to provide the necessary clearance between the spools 10 and the platform 5 (see Fig. 2); while in order to adequately brace such frame, it is connected by means of struts 13 and tie rods 14 with brackets 15 75 so that project in the same direction from the upper ends of the respective channels 2 (see Fig. 1).

Forming in effect a part of said frame 12, but lying wholly to one side thereof and of the corresponding channel 2, is a supplemental frame 16 upon which is supported the operating mechanism whereby said shaft 11, and thus the spools 10, may be rotated in proper direction or held stationary as desired. This supplemental frame is of sufficient longitudinal extent to project beyond the channels 2 on the opposite side thereof from shaft 11 and on this end of the frame is supported an electric motor 17, or equivalent prime mover. The spindle of the latter is connected by means of a roller chain drive 18 and suitable clutch mechanism 19 with an intermediate tubular shaft 20 that is transversely journaled on said frame 16, 90 being mounted on a stationary stud shaft 20^a, and is in turn connected through spur reduction gearing 21 with shaft 11.

The detail construction of clutch mechanism 19 is shown in Fig. 3, from an inspection of which it will be seen that the sprocket gear 22, that forms a part of the driving connection from the motor, is fixedly secured to the outer cone clutch member 23 and with the latter is normally freely 100 rotatable upon the shaft 20. The inner clutch member 24, however, is keyed onto

2
said shaft so as to be movable longitudinally thereof but held against rotation thereon. In order to shift clutch member 24 into and out of engagement with member 23, an operating lever 25 is provided, such lever being pivotally supported at an intermediate point on the outer end of the stationary stud shaft 20^a, that carries tubular shaft 20, and being connected with said 10
brake member by means of a fork-arm 26 that engages with a circumferentially grooved collar 27 on said member. The one end of lever 25 is provided with a suitable handle 28, while the opposite end, which 15
extends beyond shaft 20^a, is connected by means of a tension spring 29 with the frame 16 so as to be normally drawn towards such frame. A brake shoe 30, of arcuate form, is supported from a bracket 31 on frame 16 by means of a link 32 in position to be 20
pressed against the juxtaposed flat face of clutch member 24 and a projecting arm 33 on said brake shoe is pivotally connected with lever 25 at a point beyond the point of 25
its pivotal connection with shaft 20^a, the latter forming the fulcrum of said lever. From the construction just described, it will be seen that normally, under the action of spring 29, the lever 25 will be operated 30
to press said brake shoe 30 against clutch member 24, thus retaining the latter and the shaft 20, together with the connected winding spools, from turning. In other words, in this condition of the parts, the 35
platform 5 will be held stationary at whatever point it may happen to be at the time. Assuming, however, that the motor is running, if the handle of lever 25 be pressed inwardly the brake shoe 30 is moved out of 40
contact with the inner clutch member and the latter is simultaneously forced into engagement with the outer clutch member 23, as the result of which the shaft 22 is caused to rotate in unison with said outer clutch 45
member, or in other words is now driven by the motor, the direction of rotation being such as to raise the platform through the winding mechanism proper. By holding lever 25 in an intermediate or neutral position 50
so as to free inner clutch member 24 from outer clutch member 23, but without applying the brake shoe 30 with sufficient force to stop the rotation of said inner brake member, the platform may be allowed to 55
descend under its own weight at a properly regulated rate of speed.

In order to facilitate moving the elevator about, the base 1 is desirably provided with truck wheels, two different arrangements of 60
which are shown in Figs. 1 and 4, respectively. In Fig. 1, the wheels 35 (preferably two will be employed, one on each side) are mounted beneath the forwardly projecting base portion 36, so as just to contact with 65
the floor when the base 1 proper is resting thereon. However, upon tilting the structure forwardly, i. e. to the right in Fig. 1, such base 1 is raised out of contact with the floor and the structure is wholly supported 70
on said wheels 35. Handles 37 project conveniently from the opposite side of frame 12, by which the elevator structure may be thus tilted and thereupon trundled to desired position. 75
In addition to such truck wheels 35, I 75
may employ two other somewhat larger wheels 38, one on each side of the base, such wheels being mounted on studs 39 that project laterally from the corresponding channels 2. Such wheels 38, however, extend 80
downwardly a trifle below the bottom plane of base 1, as shown in Fig. 4, it being to this plane that wheels 35 at the most extend. The function of the added wheels 38 is to facilitate the turning of the elevator about 85
in a circumscribed space as may be necessary in a box car for example, the use of wheels 35 to move the structure about being in no wise interfered with. 90
Other modes of applying the principle of my invention may be employed instead of the one explained, change being made as regards the mechanism herein disclosed, provided the means stated by any of the following claims or the equivalent of such 95
stated means be employed. 95
I therefore particularly point out and distinctly claim as my invention: 100
1. In a portable elevator, the combination of a base; two spaced, vertical standards on said base; a platform vertically movable between and guided by said standards; a frame projecting laterally from said standards; a transverse shaft journaled on said frame near its outer edge; cables and cable-winding mechanism connecting said shaft and platform for raising and lowering the latter; truck wheels mounted on said base on the opposite side of said standards from said frame, said wheels clearing the bottom plane of said base; handles projecting from the latter; and other larger truck wheels attached to said standards, one on each side of said base and extending below the bottom plane of the latter. 105
110
2. In a portable elevator, the combination of a base; two spaced, vertical standards on said base; a platform vertically movable between and guided by said standards; a frame projecting laterally from said standards; brackets projecting laterally from said standards above said frame; struts and tie-rods connecting the latter with said brackets; a transverse shaft journaled on said frame near its outer edge; cables and cable-winding mechanism connecting said shaft and platform for raising and lowering the latter; and mechanism adjacent one side of said frame for 115
operating said shaft. 120
125
130

3. In a portable elevator, the combination of a base; two spaced, vertical standards on said base; a platform vertically movable between and guided by said standards; a frame projecting laterally from said standards; a transverse shaft journaled on said frame near its outer edge; cables and cable-winding mechanism connecting said shaft and platform for raising and lowering the latter; mechanism adjacent one side of said frame for operating said shaft, said mechanism including a motor, an intermediate shaft geared to said first-named shaft, a loose-running clutch member on said intermediate shaft geared to said motor, a co-operative clutch member keyed to said shaft, a lever operatively connected with said second clutch member, and a brake for the latter. 35
- 10 4. In a portable elevator, the combination of a base; two spaced, vertical standards on said base; a platform vertically movable between and guided by said standards; a frame projecting laterally from said standards; a transverse shaft journaled on said frame near its outer edge; cables and cable-winding mechanism connecting said shaft and platform for raising and lowering the latter; mechanism adjacent one side of said frame for operating said shaft, said mechanism including a motor, an intermediate shaft geared to said first-named shaft, a loose-running clutch member on said intermediate shaft geared to said motor, a co-operative clutch member keyed to said shaft, a lever operatively connected with said second clutch member, a tension spring connected with said lever and normally tending, through said lever, to retain said second clutch member out of engagement 40
- 15 with said first clutch member, and a brake shoe for said second clutch member connected with said lever so as to be pressed against said member by the action of said spring. 45
- 20 5. In a portable elevator, the combination of a base; two spaced, vertical standards on said base; a platform vertically movable between and guided by said standards; a frame projecting laterally from said standards; a transverse shaft journaled on said frame near its outer edge; cables and cable-winding mechanism connecting said shaft and platform for raising and lowering the latter; mechanism adjacent one side of said frame for operating said shaft, said mechanism including a motor, an intermediate shaft geared to said first-named shaft, a loose-running clutch member on said intermediate shaft geared to said motor, a co-operative clutch member keyed to said shaft, a lever operatively connected with said second clutch member, a tension spring connected with said lever and normally tending, through said lever, to retain said second clutch member out of engagement 50
- 25 with said first clutch member, and a brake shoe for said second clutch member connected with said lever so as to be pressed against said member by the action of said spring. 55
- 30

Signed by me this 18th day of April, 1924.

JACOB DOELCHER.
